Broadcasting System, Inc., New York, N.Y.

Filed May 11, 1970, Ser. No. 22,920

Term of patent 14 years

Int. Cl. D17—01

U.S. Cl. D56—2

FIG. 3.

FIG. 4.

FIG. 5.

FIG. 1 is a perspective view of an electric piano embodying my new design;

FIG. 2 is a top plan view thereof;

FIG. 3 is a rear elevation thereof;

FIG. 4 is a side elevation thereof; and

FIG. 5 is a front elevation.

The side shown at the left in FIG. 1 is a mirror image of the side shown in FIG. 4. The bottom of the piano is plain.

Portions of the drawing figures are lined to indicate contrast in appearance.

I claim:

The ornamental design for an electric piano, substantially as shown and described.
